UNITED STATES PATENT OFFICE

2,591,150

PAPER FEEDING MECHANISM FOR
STATISTICAL MACHINES

Sidney Robert Haines, West Norwood, London, England, assignor to Powers-Samas Accounting Machines Limited, London, England, a British company

Application November 7, 1950, Serial No. 194,458
In Great Britain November 8, 1949

9 Claims. (Cl. 235—61.9)

1

This invention relates to paper feeding mechanism for statistical machines such for example as record card controlled tabulating machines.

It has been proposed to provide a record card controlled tabulating machine with a paper feeding mechanism which could be set to feed the paper either one line space or two line spaces at each item printing operation together with means operative under the control of the total printing mechanism to feed the paper by an additional line space after a printing of a total when the mechanism was set to feed the paper by one line space at each item printing operation.

When, however, the mechanism was set to feed the paper two line spaces at each printing operation this extent of feed could not be increased under the control of the total printing mechanism so that if the items were spaced two lines apart the total was separated from the last item of the group by the same amount.

It has also been proposed in United States Patent No. 2,256,693 to provide a paper feeding mechanism with an adjustable stop having a plurality of stepped faces formed thereon to co-operate with an actuating member for the driving member for the paper feeding mechanism, the steps on the stop determining the extent of paper feeding, means being provided and operative under the control of the total-taking mechanism of the machine to adjust the relative positions of the settable stop and the driving member in such a way as to increase the length of paper feed at a total-taking operation whatever the original setting of the settable stop.

However, with mechanism as described in the above Patent No. 2,256,693 the spacing effected during a total taking cycle of the machine always remains constant.

It is an object of the present invention to provide a paper feeding mechanism having a greater capacity for adjustment than is possible with mechanisms as described above and with this object in view it is proposed, in accordance with the invention, to provide a plurality of adjustable control stops each of which is associated with a predetermined machine function and is settable independently of each of the other control stops to determine which of a number of line spacings is effected during a machine cycle

2

in which the particular machine function is being formed.

According to the invention there is provided in a record card controlled statistical machine paper feeding mechanism comprising a driving member which during its idle movement is caused to follow the movement of an actuating member having a constant stroke until arrested by an adjustable control-stop placed in its path and during the return movement of the actuating member is picked up and driven positively thereby to effect a feed stroke, characterised in that two or more control-stops are independently settable from an inactive position to one of a plurality of predetermined active positions each to arrest the driving member during its idle movement at a predetermined position whereby the mechanism may be set to feed paper by a predetermined number of line spaces at each machine operation, the actuating member being normally positioned to co-operate with a selected one of said control-stops and locating means being operable to condition the actuating member for co-operation with another control-stop only during a machine cycle during which a predetermined function of the machine is being performed.

In one embodiment of the invention there are provided three control-stops settable respectively to co-operate with the actuating member during item, total, and card-operated cycles of the machine.

In order that the invention may be more clearly understood one embodiment thereof will now be described, by way of example, as applied to a record card controlled tabulating machine and with reference to the accompanying diagrammatic drawings in which:

Figure 1 is a side elevation of mechanism according to the invention,

Figure 2 is a side elevation similar to that shown in Figure 1 but drawn to an enlarged scale with some parts omitted more clearly to show details of the construction,

Figure 3 is a plan of a part of the mechanism shown in Figure 1,

Figure 4 is a side elevation of additional control mechanism according to the invention, some parts being omitted more clearly to show details of the construction, and

Figure 5 is a scrap view of a part of the mechanism shown in Figure 4, some of the elements being shown in positions different to those which they occupy in Figure 4.

In the mechanism illustrated in Figures 1, 2 and 3 two settable control-stops are provided, one for determining the line spacing during item or listing cycles of the machine and the other for independently determining line spacing during total-taking cycles of the machine. If desired a further control-stop, as will be described with reference to Figures 4 and 5, may be incorporated in the mechanism independently to determine the line spacing as a result of what will be referred to herein as a card-operated cycle of the machine, that is, co-operation between the card-operated control stop and an actuating member, described below, will occur only when a predetermined control hole is sensed in a record card.

Referring to Figures 1, 2 and 3 the paper is fed by rotating the platen 1 through a ratchet mechanism operated by a reciprocating actuating member in the form of a rack 2. Reciprocation of the rack causes oscillation of a driving member shown as a wheel 3 and the ratchet mechanism is disposed between the wheel 3 and the platen 1.

The ratchet mechanism is well known and forms no part of the invention. It may comprise a pair of ratchet wheels mounted concentrically, one on a shaft driven by the wheel 3 and the other on the platen shaft. The ratchet teeth on one wheel face those on the other wheel and the teeth are held in engagement by a spring. Rotation of the driving member in one direction causes the driven wheel to rotate also whereas when the driving member is rotated in the opposite direction the ratchet teeth force the driving member away from the driven wheel against the action of the spring so that no movement is imparted to the platen. The ribbon feed which is of known form is driven by the actuating member 2.

As viewed in the drawings, movement of the actuating member 2 to the left is idle while movement thereof to the right drives the platen.

The actuating member 2 has a projection 4 which, in the position of rest of the machine, is held against a roller 5 supported by an arm 6 secured to the face of a disc 7 freely mounted on the sector restoring shaft 8 of the tabulator. In this position the rack is at the end of its feeding stroke and the projection 4 is held against the roller 5 by a spring 5a as described in Patent No. 2,256,693 referred to above.

The disc 7 carries a pin 9 which abuts against an arm 10 secured to the sector-restoring shaft 8 which, as described in United States specification No. 2,242,095 is oscillated from the main shaft of the tabulator at each revolution thereof by means of the arm 10 and a link 11.

At each revolution of the main shaft the sector-restoring shaft 8 is rocked counter-clockwise as viewed in the drawings and then back again. When the shaft 8 rocks counter-clockwise the projection 4 bearing on the roller 5 under the action of the spring above mentioned turns the disc 7 until a lug 12 on the actuating member 2 engages one or the other of a pair of abutments 13, 14 provided respectively on an item control-stop 15 and a total control-stop 16, Figure 2.

The control-stops 15 and 16 are mounted in side by side relation as shown in Figure 3 and each is provided with a slot 17 by which the plates are supported for lengthwise sliding movement in a straight line on pins 18 and 19 secured

in side plates 20 and 21, Figure 3. The plate 21 is omitted in Figure 2 for the sake of clarity.

Connected to the item control-stop 15 is a setting member 22 which is pivoted on the pin 18 and has a laterally projecting pin 23 which is engaged in a slot 24 in the item control-stop 15. The setting member 22 is provided with an adjusting member 25 which comprises, in known manner, a plunger 26 spring-urged to the position shown in the drawings but which can be withdrawn to the left, as viewed in Figure 2 by axial movement of the adjusting member 25. The plunger 26 is arranged to be inserted into one or other of a number of notches 27, Figure 1, formed in the side plate 21. When the plunger 26 is located in the uppermost notch the control member 15 is moved to its inactive or cut-out position and the notches below this position represent respectively, in progressive order, line space positions equivalent to one, two, three, four, five or six line spacings. As shown in Figure 2 the item control-stop 15 is set in active position to produce a line spacing the equivalent of five line spacing positions. Thus after the lug 12 on the actuating member has engaged the abutment 13 the actuating member imparts to the driving member 3 an angular movement such that the paper is advanced by a distance equal to five line spaces.

The total control-stop 16 has associated therewith a setting member 28 which is also pivoted on the pin 18 and is provided with a lateral pin 29 extending into a slot 30 in the control-stop 16. The setting member 28 is provided with an adjusting member 31 similar to the adjusting member 25 described above. The plunger 32 associated with the adjusting member 31 co-operates with notches 33 in the side plate 20, the notches 33 being arranged in the same spaced relation as those in the side plate 21 and including a cut-out or inactive position. As shown in Figure 2 the total control-stop 16 is set at the one line space position so that after engagement of the abutment 14 by the lug 12 on the actuating member 2 the actuating member imparts to the driving member 3 an angular movement such that the paper is advanced by a distance equal to one line space.

From the foregoing it will be understood that the control-stops 15 and 16 are independently settable for engagement by the lug 12 on the actuating member 2 and the line setting effected by one of the control-stops is not affected by the setting of the other.

To permit co-operation between either of the control-stops and the lug 12 the abutments 13 and 14 on the control-stops 15 and 16 are offset with respect to the control-stops so that the abutments are disposed one above the other and are movable in the plane in which the lug 12 is movable.

Normally the actuating member 2 is positioned as shown in Figure 2 so that the lug 12, on forward movement of the actuating member 2, will co-operate with the abutment 13 on the item control-stop 15. During the operation of the machine the lug 12 will co-operate with the abutment 13 during each item or listing cycle but when a total cycle occurs the actuating member 2 is lowered so that the lug 12 is aligned with the abutment 14 on the total control-stop 16.

To condition the actuating member 2 so that the lug 12 carried thereby will co-operate with the abutment 14 there is provided locating means 75 which includes an angularly movable lever 34

freely mounted on the total-shaft 35 of the machine, the lever 34 having a lateral pin 36 on which is supported a roller 37 to roll in a slot 38 formed in the actuating member 2. The lever 34 is connected by a spring 39 with an arm 40 which is secured to the total shaft 35. A pin 41 extends laterally from the arm 40 and is arranged to engage an edge of the lever 34.

The actuating member 2 is guided on a roller 42, Figure 1, having large flanges 43 so that the actuating member can swing about the driving member 3 on actuation of the total-shaft 35. Thus, on a total cycle of the machine the shaft 35 is rocked clockwise, as viewed in Figure 2, and the actuating member 2 is swung about the roller 42 so that the lug 12 is brought into alignment with the abutment 14 and on being moved downwards, as viewed in Figure 2, the lug 12 co-operates with the abutment 14 to determine the number of line spacings by which the total is spaced from the next item to be printed on the paper.

To render the paper feed mechanism inoperative during item sensing cycles of the machine, but operative during a total cycle, the item control-stop 15 is moved to the cut-out position, the total control-stop 16 being adjusted to the desired line spacing. When the control-stop 15 is in the cut-out position a dwell 44 formed in the setting member 22 is disposed beneath a pin 45 extending laterally from one arm of a bell crank 46 pivoted at 47 to the side plates 20, 21. The other arm of the bell crank is engaged by a spring post 48 extending laterally from a link 49 the upper end of which is pivotally connected to an arm 50 secured to a spindle 51 carrying a shutter 52 adapted to lock the printing hammers so that they are rendered inoperative until the total-shaft 35 is rocked.

The link 49 is pulled upwards to hammer locking position by a spring 53, the bell crank being moved about its pivot 47 so that the pin 45 is in engagement with the dwell 44 in the setting plate 22. The link 49 will remain in this position until a total taking cycle when the total-shaft 35 is rocked clockwise and a pin 54 on the arm 40 then engages a lug 55 on the link 49 so that as the lug 12 is moved into alignment with the abutment 14 the link 49 is simultaneously pulled downwards, against the action of its spring 53, thereby rocking the spindle 51 to release the print hammers for operation.

The link 49 is provided with a further lug 56, Figure 1, which, during the period that the link 49 is in its up position, is engaged with a shoulder 57 on the disc 7 thus preventing actuation of the ribbon feeding mechanism. When the link 49 is moved downwards, as above described, the lug 56 is moved out of engagement with the shoulder 57 so that on rotation of the disc 7 by the actuating member 2 the ribbon feeding mechanism is actuated.

On restoration of the total-taking shaft 35 to its starting position the lug 12 is again raised to the position shown in Figure 2 and the spring 53 again moves the link 49 upwards so that the hammers are locked. The lug 56 again engages the shoulder 57 to render the ribbon feeding mechanism inactive until the next total-taking cycle when the shaft 35 is again rocked.

The total-shaft 35 is rocked by a cam, not shown, on the main shaft of the machine, the cam serving to lift a link 58, Figure 1, which is pivoted to a bell crank plate 59 connected by a link 60 to an arm 61 secured to the shaft 35.

When the control mechanism consist only of a unit, as described above, which includes an item control-stop and a total control-stop the unit is spaced from the frame of the machine by spacing members 62, Figure 3, but should it be desired to include a further unit adapted independently to control the line space of the paper feeding mechanism during a machine cycle other than an item printing cycle or a total-taking cycle an additional unit for this purpose is included in the space occupied by the spacing members 62. The said further unit for independently controlling the line spacing of the paper feeding mechanism is illustrated diagrammatically in Figure 4 and will now be described with reference thereto.

The unit about to be described is adapted for operation as the result of the sensing of a predetermined control hole punched in a record card and is hereinafter referred to as the card-operated control-unit. This unit comprises two side plates only one of which, indicated by the reference numeral 63, is shown in Figure 4 the other being omitted more clearly to show the detailed construction of the unit. The unit shown in Figure 4 is provided with a card-operated control-stop 64 having an abutment 65 extending at right angles thereto to project into the plane in which the lug 12 is movable. When the unit is in position in the machine the abutment 65 is disposed above the abutment 13 on the item control-stop 15. A setting plate 66 is pivoted about a pin 67 similar to the pin 18 with which it is axially aligned. A pin 68 extends laterally from the setting plate 66 and is located in a slot 69 in the control-stop 64 and the setting plate is provided with an adjusting member 70 similar to the adjusting members 25 and 31 described above. The adjusting member 70 is provided with a plunger 71 to co-operate with notches 72 formed in the side plate 63, the top notch representing the cut-out position for the unit and the remaining slots indicating different line spacings to which the control-stop may be set. The control-stop 64 is guided for movement in a straight line path by the pin 67 and a further pin 73 which is axially aligned with the pin 19, the pins 67 and 73 being located in a slot 74 formed in the control-stop 64.

As shown in Figure 4, the control-stop 64 is set in the six-line spacing position so that after the abutment 65 has been engaged by the lug 12 the actuating member moves the driving member 3 angularly to feed the paper by a distance equal to six line spaces. It will be understood that the setting of the control-stop 64 is entirely independent from any setting which may be effected by the control-stops 13, 14 although should the control-stop 13 be in its cut-out position the control-stop 64 will not be effective because in such circumstances the disc 7 is latched against rotation by the engagement of the lug 56 with the shoulder 57. If, however, the control-stop 13 is active the pin 45 is arrested by engagement with the upper surface of the setting member 22, as shown in Figure 2, and the link 49 is retained in its down position against the action of spring 53.

When employing the card-operated control unit, the lug 12 is raised for co-operation with the abutment 65 by the movable lever 34. To this end the locating means for the actuating member includes a pin 75 which extends laterally from the lever 34, the pin being located in a slot 76 formed in one end of a slide 77. The

opposite end of the slide is supported on a spindle 78, being guided for lengthwise movement by a slot 79. A spring 80 tends to urge the slide 77 to the left, as viewed in Figure 4, but a latch 81 secured to the spindle 78 is adapted to engage in a notch 82 formed in the underside of the slide 77 to retain the slide in its inactive position.

The latch 81 is urged to latching position by a spring 83 and is tripped to permit the slide to become active by an arm 34 secured to the spindle 78 and arranged to be rocked by a transmission element, indicated diagrammatically at 85, the transmission element being, as will be understood in the art, disposed in the connection box associated with the sensing mechanism, not shown, of the tabulating machine. On a predetermined control hole being sensed in a card, the transmission element 85 is moved upwards thus rocking the spindle 78 and tripping the latch 81 out of engagement with the slide 77 and the slide 77 is then moved to the left, as viewed in Figure 4, by the spring 80. As the slide 77 moves to active position the end of the slot 76 engages the pin 75 and rocks the movable lever 34 counter-clockwise, against the action of spring 39, so that the lower end of the actuating member 2 is raised to bring the lug 12 into alignment with the abutment 65 on the card-operated control-stop 64.

Secured to the disc 7 is an arm 86 to the outer end of which is pivoted a positively operated restoring member comprising a link 87 carrying a restoring pawl 88. As the shaft 8 is restored towards the end of the card-operated cycle of the machine the arm 86 is moved clockwise with the disc 7 and the restoring pawl 88 engages a tooth 89 on the slide 77 so that the slide is moved to the right, as viewed in Figure 4, until the notch 82 is moved slightly past the latch 81. As the notch 82 is moved past the latch 81, a tripping element formed on the link 87 and having a cam face 90 engages with the spring anchor post 91 so that the restoring pawl 88 is tripped out of engagement with the tooth 89 on the slide 77. The slide 77 then returns under the action of its spring 80 until the notch 82 is engaged by the latch 81 and the slide is thereby retained in its inactive position until it is again actuated as the result of a further predetermined control hole being sensed in a record card.

In order that the actuating member 2 shall not be raised in the event of the control hole being sensed in a card while the card-operated control-stop 64 is in its cut-out position, a cut-out lever 92 is pivoted on the pin 67 and is resiliently engaged with the control-stop 64 by a spring 93. When the card-operated control-stop 64 is in the cut-out position, as indicated in Figure 5, the cut-out lever 92 is positioned in the path of the end of the slide 77 so that should the latch 81 be tripped the slide 77 is prevented from moving to the left, as viewed in Figure 4, under the influence of its spring 80.

From the foregoing it will be understood that the control-stops 13, 14, and 64 can be simultaneously active and that each can be set independently of the others to effect the desired line spacing when the actuating member co-operates therewith during the operation of the machine to which the control mechanism is fitted. Similarly, any of the control-stops can be set to its cut-out position and thereby rendered inactive, but in the embodiment described above the control-stop 64 is not effective in the event that the item control-stop 13 is inactive.

It will also be understood that although the control mechanism according to the invention has been described with reference to its application to a card-controlled tabulating machine of the kind described in United States Patent No. 2,242,095 it can also be applied to other forms of card-controlled statistical machines such for example as the machine described in United States Patent No. 2,496,138.

I claim:

1. In a record card controlled statistical machine paper feeding mechanism comprising a driving member which during its idle movement is caused to follow the movement of an actuating member having a constant stroke until arrested by an adjustable control-stop placed in its path and during the return movement of the actuating member is picked up and driven positively thereby to effect a feed stroke, characterized in that two or more control-stops are independently settable from an inactive position to one of a plurality of predetermined active positions each to arrest the driving member during its idle movement at a predetermined position whereby the mechanism may be set to feed paper by a predetermined number of line spaces at each machine operation, the actuating member being normally positioned to co-operate with a selected one of said control-stops and locating means being operable to condition the actuating member for co-operation with another control-stop only during a machine cycle during which a predetermined function of the machine is being performed.

2. Paper feeding mechanism according to claim 1, wherein there are provided three control-stops settable respectively to co-operate with the actuating member during item, total and card-operated cycles of the machine.

3. Paper feeding mechanism according to claim 2, wherein the control-stops are guided for movement in planes parallel with the plane in which the actuating member is moved and each stop is provided with an abutment, said abutments being disposed relative one to the other for movement in the plane in which the actuating member is moved and thereby to co-operate with the actuating member to determine the positions in which the driving member is arrested.

4. Paper feeding mechanism according to claim 2, wherein the actuating member is normally aligned for co-operation with the abutment on the item control-stop and the locating means includes an angularly movable lever connected with the actuating member and operable during a total-taking cycle of the machine to align the actuating member for co-operation with the abutment on the total control-stop.

5. Paper feeding mechanism according to claim 4, wherein a normally inactive sliding element connected with said lever is rendered active by the sensing of a control hole in a record card fed to the machine and operates the lever to align the actuating member for co-operation with the abutment on the card-operated control-stop.

6. Paper feeding mechanism according to claim 5, wherein the sliding element is spring urged to activate position and is rendered inactive by a pivotally mounted latch movable out of latching engagement with a sliding element by a transmission element actuated by a predetermined sensing element in card-sensing mechanism associated with the machine.

7. Paper feeding mechanism according to claim

6, wherein the sliding element is movable from active to inactive position by a positively actuated restoring member arranged to co-operate with a tooth on the sliding element, a trip element being provided to trip the restoring member out of engagement with said tooth when the sliding element is restored to inactive position and is engaged by said latch.

8. Paper feeding mechanism according to claim 6, wherein a cut-out lever movable with the card-operated control-stop is arranged when the control-stop is set inactive to be positioned in the

path of the sliding element to prevent the sliding element from being rendered active by the tripping of its latch.

9. Paper feeding mechanism according to claim 5 2, wherein each control-stop is settable by a setting member connected therewith, the setting members being mounted for pivotal movement about an axis common thereto.

SIDNEY ROBERT HAINES.
